UNITED STATES PATENT OFFICE.

FRANKLIN B. MILLER, OF LOS ANGELES, CALIFORNIA.

SPRINKLER.

1,168,219.

Specification of Letters Patent. Patented Jan. 11, 1916.

Application filed May 28, 1913. Serial No. 770,524.

To all whom it may concern:

Be it known that I, FRANKLIN B. MILLER, a citizen of the United States, residing at Los Angeles, in the county of Los Angeles 5 and State of California, have invented new and useful Improvements in Sprinklers, of which the following is a specification.

This invention relates to sprinklers, and more particularly to means for attaching a 10 sprinkling device, and the principal object is to provide a nozzle with a sprinkling member.

It is also an object to provide a nozzle with means for closing off the sprinkling 15 member as desired.

It is a further object to provide a sprinkler with a support by which the latter may be readily supported in fixed and movable relation to any desired position on the 20 ground.

In the drawings accompanying this specification and forming therewith the application for Letters Patent: Figure 1 is a longitudinal sectional view through the nozzle, 25 the sprinkler being shown mainly in elevation. Fig. 2 shows the device in elevation and in position to be used as a nozzle. Fig. 3 is a detail section on the line 3—3 of Fig. 2 viewed in the direction indicated by the 30 arrows.

More specifically in the drawings, 5 designates a cylindrical tubular body portion having a threaded flanged end 6 adapted to engage with the coupling 7 of the ordinary type of garden hose and connected thereto in the usual manner with a washer 8 interposed. The oppositely disposed end of this body member is provided with a nozzle 9 which is preferably of dome shaped 35 configuration having a central concentric bore 10 therein back of which is supported the cylindrical spreader 11.

The spreader, as stated, is preferably cylindrical and its outer end is spaced a sufficient distance from the bore 10 to permit of the passage of water, the inner end being supported upon a partition 12 which is of triangular shape and extends across the walls of the body member 5 in such position 50 that it leaves arcuate openings 14 for the passage of water between the partition and the inner wall.

The outer surface of the body is pref-

erably threaded from the shoulder 16 inwardly to receive the threaded flanged end 55 of the cap 17, which is adapted to snugly fit the cylindrical walls of the nozzle member from the shoulder 16 outward and is adapted to fit either this nozzle member or the sprinkler member 18.

The sprinkler member is preferably located intermediate of the nozzle member and of the flanged end 6, and consists of a right angled extension having the same configuration externally as the nozzle member 65 9, its dome shaped top 19 being provided with a plurality of openings through which the water is distributed in any desired manner. The cylindrical portion of the shoulder 20 and the threaded section from the 70 shoulder inwardly are of the same diameter as that of the nozzle member and the cap 17, as stated, can be used and forms a proper fit on either of these members.

To support the sprinkler when desired in 75 the fixed position a sharpened stud 21 is formed on and extends from the oppositely disposed wall, and is preferably of such length as to readily support the device in relation to the ground when inserted therein, as clearly shown in Fig. 1.

The operation of the device will be readily understood from the drawings and description thereof, Fig. 1 showing the cap on the nozzle member and the adaptation to 85 sprinkling a lawn, Fig. 2 showing the cap securely covering the sprinkler member and preventing the exit of water therefrom, the distributing plate 12 compelling the water to come in such relation to the inner surface 90 of the dome 9 that an efficient and equable spray is formed through the exit or bore 10.

What I claim is:

In a device such as described the combination with a hollow body portion having 95 means at one end thereof for engaging a source of fluid supply, outlet nozzles extending integrally from the body and communicating therewith, one in alignment with the body and the other at right angles thereto, 100 said nozzles being of corresponding shape and size and including tubular members having rounded ends and enlarged shoulders provided with exterior threads adjacent the inner ends of the nozzles, and a removable cap for alternately closing the noz-

zles including a tubular member closed at its outer end and interiorly threaded at its inner end for engaging the threads upon said shoulders and a ring formed within said closure for engaging the exterior surface of the nozzles and adjacent sides of the shoulders forming a tight joint.

In witness that I claim the foregoing I have hereunto subscribed my name this 19 day of May, 1913.

FRANKLIN B. MILLER.
